UNITED STATES PATENT OFFICE.

WILLIAM GEORGE BEATTY, OF FERGUS, ONTARIO, CANADA.

CARRIER.

Application filed January 4, 1922. Serial No. 527,028.

To all whom it may concern:

Be it known that I, WILLIAM GEORGE BEATTY, a British subject, and resident of the town of Fergus, in the county of Wellington and Province of Ontario, Dominion of Canada, have invented certain new and useful Improvements in Carriers; and I hereby declare that the following is a full, clear, and exact description of the same.

10 My invention relates to that type of carrier in which the rope gripping jaws open and close in parallel planes and are actuated by an oscillatory lock whose movement for the closing of the jaws is controlled by a detent and tripping lever; and it relates more particularly to the construction and operation of the detent controlling the oscillation of the lock for the closing of the jaws, and to the construction of the tripping lever actuating the detent.

15 In my Patent No. 1,367,653, a rocking detent is employed to engage the lock and control its oscillation for the closing of the rope gripping jaws which, owing to the limitation of its rocking movement, must be accurately ground to properly function, as otherwise it fails to release the lock if insufficiently ground and fails to hold it if overground.

20 In the same patent the tripping lever for releasing the detent from the lock, consists of a single lever arm fulcrumed at one end to the frame of the apparatus and provided at the other end with a relatively 25 stationary rope guide which in the practical use of the carrier causes the abrasion of the hoisting rope when running over the hoisting pulley.

25 My present invention is directed to these two features of the apparatus and has for its objects:—

(a) To provide the lock with a reciprocating detent, so constructed that it will, regardless of the accuracy of its manufacture, positively engage the lock and prevent its oscillation when maintaining the rope gripping jaws in their open position, and positively release the lock for the closing movement of the jaws when actuated by the tripping lever; and

(b) To provide the tripping lever with a rope guide which will automatically adapt itself to the lateral movement of the hoisting rope when running over the hoisting pulley as hereinafter set forth and particularly pointed out in the claims.

In the drawings:—

Fig. 1 is a side elevational view of the carrier with the lock oscillated to open the rope gripping jaws for the run of the hoisting rope.

Fig. 2 is a sectional elevational view of the same with the car omitted and the lock oscillated to close the rope gripping jaws on the hoisting rope.

Fig. 3 is a fragmentary sectional end elevational view showing the construction of the detent with the lock in the same position as in Fig. 1.

Fig. 4 is a similar view to Fig. 3 with the lock in the same position as in Fig. 2.

Fig. 5 is a sectional plan view of the tripping lever and rope guide.

Fig. 6 is a fragmentary detail view of the lock and detent with the parts in the position shown in Fig. 3, and

Fig. 7 is an end elevational view of the lock in the position shown in Fig. 6.

Like characters of reference refer to like parts throughout the specification and drawings.

As the general construction of the carrier is similar to the disclosure in my United States patent above referred to, it will not be necessary to describe it in detail further than so far as the parts relate to this invention.

The rock shaft *g* is journaled in the frame *a* and is provided with a crank *g'* having an eye *g''* to which is connected one end of the hoisting rope *d*. Mounted on the rock shaft *g* is a lock *h* controlling the opening and closing movement of the rope gripping jaws *r, r'*. This lock is of any usual or approved type and its upwardly extending forks *h', h''* are symmetrically arranged on opposite sides of its transverse axis.

Extending laterally from the sides of the lock at approximately the bottom of the 100 forks are two curved webs *h³* terminating in downwardly extending detent shoulders *h⁴*. Opposed to the lock *h* is the detent *j* which controls its oscillation for the closing movement of the rope gripping jaws. 105 Extending laterally from the upper part of the sides of the detent are guides *j⁴* entered in corresponding vertical guideways *a'* on the inner surfaces of the frame *a*. At the lower end of the detent is a transversely arranged hub *j'* for the hinge bolt *c*, which extends through the lugs or

flanges h' of the tripping lever k and hingedly connects the detent and tripping lever together. In the upper end of the detent is an aperture or through slot j^3 of such dimensions as will permit of the fork h' , the webs h^3 and detent shoulders h^4 , moving freely through it during the oscillation of the lock. In the preferred construction the detent consists of an apertured plate in which the aperture or through slot j^3 occupies the greater portion of the upper part of its structure and is contracted to approximately the width of the fork h' where the slot extends through the top of the detent. This arrangement provides the detent with two detent members j'' which engage the detent shoulders h^4 of the lock when the latter is oscillated to maintain the rope gripping jaws in their open position.

The depth of the detent shoulders h^4 is proportioned to the lifting movement of the detent and the width of the shoulders is such as to extend beyond the sides of the through slot j^3 and engage the detent members j'' when the lock is oscillated to open the rope gripping jaws r, r' . When the jaws r, r' are open the detent and tripping lever, as shown in Figs. 1, 3 and 6, are at the limit of their downward movement with the members j'' engaging the detent shoulders h^4 and preventing the oscillation of the lock for the closing movement of the jaws until the tripping lever has been actuated to disengage the members j'' from the detent shoulders.

The tripping lever K is fulcrumed at l to the frame a and extends from its fulcrum to a point below the detent j . In the tripping lever k , below the detent j is a transverse slot e , and pivoted at m^2 to the under side of the tripping lever k , between its fulcrum l and the slot e , is one end of an oscillating guide arm m . Extending from the guide arm m through the slot e is a bolt m' having a washer m'' engaging the upper side of the tripping lever k and overlapping the edges of the slot e . The pivot m^3 oscillatingly connects the guide arm m to the guide tripping lever k and the bolt m' , washer m'' and slot e provide for the oscillating movement of the guide arm between the positions shown in full and dotted lines in Fig. 5. In the guide arm m is a rope guide m^4 for the hoisting rope d in its run to the hoisting pulley o and rope gripping jaws r, r' . The hoisting pulley o is swivelled to the frame a to automatically adapt itself to the inclination of the hoisting rope d .

During the run of the hoisting rope through the rope guide m^4 to the hoisting pulley, the guide arm m automatically adapts itself to the inclination of the rope and overcomes, to a great extent, the abrasion or wear of the rope heretofore result-

ing from passing through an immovable guide. When the load is lifted to the limit of its movement, the sling pulleys p come into contact with the guide arm m and lift the tripping lever and detent to the limit of their upward movement, this limit of movement being sufficient to release the detent members j'' of the detent from the detent shoulders h^4 of the lock. When the detent members j'' are released from the shoulders h^4 the lock oscillates into the position shown in Figs. 2 and 4 this oscillation of the lock being caused by the weight of the load on the crank g' of the rock shaft g .

During the oscillation of the lock into the position shown in Figs. 2 and 4 the fork h' , webs h^3 and detent shoulders move through the slot j^3 and the curved webs h^3 ride against the under side of the detent members j'' and lift the detent and tripping lever into the position shown in Fig. 2 and the oscillation of the lock closes the jaws r, r' on the hoisting rope. When the fork h' engages the stop block p' the lock oscillates into the position shown in Figs. 1 and 5 and the detent and the tripping lever then move to their limit of movement in a downward direction to the position shown in Fig. 3, in which position the detent members j'' engage the shoulders h^4 , and prevent the oscillation of the lock until the tripping lever is again actuated.

The sides of the detent are provided with lugs j^5 below the guides j^4 and spaced therefrom, and the frame a is provided with side bars j^6 extending through the space between the lugs j^5 and guides j^4 , this space being equal to the movement of the detent to clear the detent shoulders h^4 for the oscillation of the lock. This construction provides a convenient means for limiting the movement of the detent and tripping lever when actuated to release the lock for its oscillation during the closing of the jaws and when returning to a normal position when the lock is actuated to again open the jaws.

For the manual operation of the detent, the frame is provided with a grooved idler t and a pull rope s connected to the detent and passed over the idler.

Passing through the frame a at the opposite end to the rock shaft g is a bolt r^2 and in front of this bolt is a second bolt r^3 . Suspended from the bolts r^2, r^3 are two sets of links r^4, r^5 each of which has two sets of eyes r^6, r^7 in oblique alignment to receive the pintles r^8, r^9 of the rope gripping jaws r, r' which owing to this construction open and close in parallel planes. Pivotedly connected to the links r^4 is a U-shaped coupling member r^{10} having an axial bore r^{11} through its head r^{12} for the draw bar r^{13} .

One extremity of the draw bar is of hook-shaped formation and engages in an eye

r^{14} in the lock h and the other extremity is screw-threaded and extends through the bore r'' .

The screw-threaded extremity of the draw-bar is provided with adjusting nuts r^{15} r^{16} arranged on opposite sides of the head r^{12} to regulate the closing movement of the jaws to the size of the hoisting rope. For example, the nuts can be positioned to 10 adjust the jaws to close tightly against a hoisting rope of the smallest size or they can be adjusted to close tightly against a rope of the largest size or they can be adjusted to close tightly against a rope of any 15 size intermediate the largest and smallest sizes.

When the hoisting rope elevates the sling pulleys to engage the guide arm m and actuate the tripping lever, the latter lifts 20 the detent clear of the shoulders h^4 . The lock h , under the weight of the load on the arm g' , then oscillates to the position shown in Fig. 2 and closes the rope gripping jaws, and remains in this position until 25 it comes into engagement with the stop block p' which turns into the position shown in Fig. 1 in which position it is engaged and held by the detent. In this latter 30 position of the lock the rope gripping jaws are open and the hoisting rope is free to run. The stop block is stationarily fixed to the track at the loading position.

Having thus fully described my invention, what I claim as new and desire to 35 secure by Letters Patent is:—

1. A carrier comprising rope gripping jaws, an oscillatory lock for opening and closing said jaws, and a reciprocating detent co-acting with and engaging the lock 40 for holding the jaws in their open position and apertured for the movement of the lock therethrough during its oscillations, said aperture being so positioned in the detent as to be out of line with the lock when the 45 detent is reciprocated to engage the lock and prevent its oscillation while the jaws are in their open position and to be in the path of the lock when the detent is reciprocated to release the lock for its oscillation between the jaw opening and closing positions.

2. A carrier comprising rope gripping jaws, an oscillatory lock for opening and closing said jaws, and a reciprocating detent co-acting with and engaging the lock 55 for holding the jaws in their open position and apertured for the movement of the lock therethrough during its oscillations, said aperture being so positioned in the detent as to be out of line with the lock when the 60 detent is reciprocated to engage the lock and prevent its oscillation while the jaws are in their open position and to be in the path of the lock when the detent is reciprocated to release the lock for its oscillation between the jaw opening and closing posi-

tions, and means for actuating the detent.

3. A carrier comprising rope gripping jaws, an oscillatory lock for opening and closing said jaws, and a reciprocating detent co-acting with and engaging the lock 70 for holding the jaws in their open position and apertured for the movement of the lock therethrough during its oscillations, said aperture being so positioned in the detent as to be out of line with the lock 75 when the detent is reciprocated to engage the lock and prevent its oscillation while the jaws are in their open position and to be in the path of the lock when the detent is reciprocated to release the lock for its 80 oscillation between the jaw opening and closing positions, and a tripping lever fulcrumed to the carrier and connected with the detent.

4. A carrier comprising rope gripping 85 jaws, an oscillatory lock for opening and closing said jaws, and a reciprocating detent co-acting with and engaging the lock for holding the jaws in their open position and apertured for the movement of 90 the lock therethrough during its oscillations, said aperture being so positioned in the detent as to be out of line with the lock when the detent is reciprocated to engage the lock and prevent its oscillation while 95 the jaws are in their open position and to be in the path of the lock when the detent is reciprocated to release the lock for its oscillation between the jaw opening and closing positions, and guide-ways for the 100 reciprocating movement of the detent.

5. A carrier comprising an oscillatory lock having a detent surface, a pair of rope gripping jaws, opened and closed by the lock, a reciprocating detent apertured for 105 the oscillation of the lock and provided with a detent member engaging the detent surface of the lock when oscillated to maintain the rope gripping jaws in an open position, and means actuating the detent and releasing its detent member from the detent surface of the lock for its oscillation through the aperture to close the rope gripping jaws.

6. A carrier comprising an oscillatory lock having a detent surface, a pair of rope 115 gripping jaws, opened and closed by the lock, a reciprocating detent apertured for the oscillation of the lock and provided with a detent member engaging the detent surface of the lock when oscillated to maintain the rope gripping jaws in an open position, and a tripping lever actuating the detent and releasing its detent member from the detent surface of the lock for its oscillation through the aperture to close the rope gripping jaws. 120

7. A carrier comprising an oscillatory lock having a detent surface, a pair of rope gripping jaws, opened and closed by the lock, a reciprocating detent apertured for 130 the oscillation of the lock and provided with

- a detent member engaging the detent surface of the lock when oscillated to maintain the rope gripping jaws in an open position, a tripping lever actuating the detent and releasing its detent member from the detent surface of the lock for its oscillation through the aperture to close the rope gripping jaws, and means hingedly connecting the detent with the tripping lever.
10. 8. A carrier comprising an oscillatory lock, a pair of rope gripping jaws opened and closed by the lock, a reciprocating detent engaging the lock when oscillated to maintain the rope gripping jaws in an open position, a tripping lever actuating the detent and releasing it from the lock for its oscillation to close the rope gripping jaws, and stops limiting the reciprocating movement of the detent.
15. 9. A carrier comprising an oscillatory lock having curved webs extending laterally from its sides and terminating in detent engaging shoulders, a pair of rope gripping jaws opened and closed by the lock, a reciprocating detent apertured for the oscillation of the lock and provided with a detent member engaging the detent shoulders of the lock when oscillated to maintain the rope gripping jaws in an open position, and means actuating the detent and releasing it from the lock for its oscillation to close the rope gripping jaws.
20. 10. A carrier comprising an oscillatory lock having curved webs extending laterally from its sides and terminating in detent engaging shoulders, a pair of rope gripping jaws opened and closed by the lock, a reciprocating detent apertured for the oscillation of the lock and provided with a detent member engaging the detent shoulders of the lock when oscillated to maintain the rope gripping jaws in an open position, and means actuating the detent and releasing it from the lock for its oscillation to close the rope gripping jaws.
25. 11. A carrier comprising a tripping lever consisting of an arm fulcrumed at one end to the carrier, an oscillating arm pivoted at one end to the lever arm and provided at the other end with a rope guide, and a sliding connection between the oscillating arm and the lever arm.
30. 12. A carrier comprising a tripping lever consisting of an arm fulcrumed at one end to the carrier and formed with a transverse slot, an oscillating arm pivoted at one end to the lever arm and provided at the other end with a rope guide, and a sliding connection between the oscillating arm and the lever arm extending through said slot.
35. 13. A carrier comprising a tripping lever consisting of an arm fulcrumed at one end to the carrier and formed with a transverse slot, an oscillating arm pivoted at one end to the lever arm and provided at the other end with a rope guide, a sliding connection between the oscillating arm and the lever arm extending through said slot, an oscillatory lock, and a reciprocating detent for the lock actuated by the tripping lever.

Dated at the said town of Fergus, this 20th day of December, A. D. 1921.

WILLIAM GEORGE BEATTY.
